[57] CLAIM

The ornamental design for a cattle chute, substantially as shown and described.

DESCRIPTION

FIG. 1 is a left front perspective view of a cattle chute showing our new design.

FIG. 2 is a bottom right rear perspective view thereof.

FIG. 3 is a left side elevational view thereof in its extended position, and with the trailer hitch assembly in a vertical collapsed position.

The top surface of the floor deck of the cattle chute is understood to be flat and unornamented.
